UNITED STATES PATENT OFFICE.

VERGIL MULHOOLLAND, OF WEST HARTFORD, CONNECTICUT, ASSIGNOR TO HARTFORD-EMPIRE COMPANY, OF HARTFORD, CONNECTICUT, A CORPORATION OF DELAWARE.

APPARATUS FOR ANNEALING GLASSWARE.

Application filed August 27, 1925. Serial No. 52,752.

This invention relates to apparatus for annealing glassware, and it has particular relation to lehrs of the tunnel type, through which articles of glassware are transported by an endless conveyor, and in which they are subjected to varying temperature environments, in order to relieve stresses and strains that may exist in the ware or that may develop therein after their removal from the molds of a shaping machine.

One of the objects of the present invention is to improve upon the conveyors employed in lehrs of the character described, by providing an endless conveyor, the lateral edges of which extend without the heated tunnel and to which the driving chains are secured where they will not be subject to the high temperature of the tunnel and where they will be conveniently accessible for replacement or repair.

In the accompanying drawing:

Figure 1 is a diagrammatic view, partly in side elevation and partly in vertical longitudinal section, of a lehr embodying the invention;

Fig. 2 is an enlarged fragmentary transverse sectional view through the lower portion of the tunnel illustrating the location of the conveyor driving chains relative to the tunnel; and

Fig. 3 is an enlarged fragmentary side elevation of the conveyor and a driving chain.

Referring to the drawing:

A lehr constructed according to the invention is shown diagrammatically in Fig. 1 as comprising a tunnel A; a plurality of heating flues B extending longitudinally beneath the tunnel; a plurality of cooling flues C extending longitudinally above the tunnel; a fire box D located beneath the receiving end of the tunnel and communicating with the heating flues B; a draft-producing device E such as a suction fan, located above the discharge end of the tunnel and communicating with both the heating flues B and the cooling flues C; an endless conveyor F the ware-bearing stand of which traverses the tunnel and the idle strand of which returns to the receiving end of the tunnel beneath the lehr, and a conveyor driving mechanism G.

The tunnel A comprises a plurality of sections 1 arranged in end-to-end relation and

supported by a frame work 2. Each of the sections 1 comprises a bottom 3, side walls 4 and a top 5. The bottoms 3 consist of a plurality of shell-like members (Fig. 2) preferably of cast iron, which are arranged in side-by-side relation to form the heating flues B. These members are formed with corrugated upper and lower surfaces 7 and 8, respectively, in order to provide relatively great heat radiating surfaces in proportion to their width and to reduce the area of contact with the bottom of the conveyor. The members 6 are supported by a plurality of T-bars 9 carried by the frame work 2 and their sides and bottoms are surrounded by a powdered insulating material 10 contained in a sheet metal casing 11.

The side walls 4 comprise a sheet metal casing 12 containing a powdered insulating material 13 and are supported in spaced relation to the bottom 3 by longitudinally extending Z bars 14 which are secured to the casing 11 and project outwardly therefrom. The inner faces of the walls 4 are formed with a plurality of vertical corrugations 13a which gives increased heat radiating surface and tends to make a uniform temperature transversely of the tunnel.

The top 5 of the tunnel may be of any preferred heat-insulated construction, for example, such as that disclosed in my copending application Serial No. 33,977, filed June 1, 1925, and is covered by heat-insulating material 15.

The fire box D comprises a combustion chamber 16 which communicates with the forward ends of the heating flues B through a damper-controlled passageway 17. The heated gases from the fire box D and the cooling air from the outer atmosphere are drawn through the heating flues B and through the cooling flues C, respectively, by the draft-producing device E consisting of a motor-driven suction fan 18 mounted upon the tunnel adjacent to the rear or exit end thereof. This fan communicates with a wind box 19 which, in turn, communicates with the flues B through vertical branch pipes 20 disposed one on each side of the tunnel.

The wind box 19 also communicates with a wind pipe 21 which extends longitudinally above the tunnel and which communicates

with the cooling flues C at intervals through damper-controlled stacks 22.

A plurality of damper-controlled stacks 23 communicating with the outer atmosphere, are provided at intervals along the heating flues B for the purpose of admitting air from the outer atmosphere into these flues in regulable quantities whereby the gases therein may be diluted and cooled at 10 the desired points and in the proper amounts to obtain the required temperature drop in the tunnel.

The conveyor F comprises a plurality of flat woven wire mats or pans 24 which are 15 slidably supported upon the floor of the tunnel and which extend laterally beneath the side walls where they are connected together by side sprocket chains 25. These chains ride upon the horizontal portions of 20 the Z bars 14, which constitute tracks therefor, and are driven by the driving mechanism G. This mechanism consists of a drum 27 which is mounted on a shaft 28 and around which the several pans pass and side 25 sprocket wheels 29 which drive the chains 25. The mechanism G is actuated from any suitable source of power through a gear wheel 30, shaft 31, worm 32 and worm gear 33 which latter is fixed to the shaft 28.

30 The idle strand of the conveyor F is supported beneath the lehr by rails 34 carried by the framework 2.

The ware is prevented from engaging the stationary side walls and from becoming 35 displaced from the conveyor during its passage through the tunnel by side angle members 35 which are also preferably constructed of woven wire fabric and which are secured to the outer edges of the pans 24 by 40 means of angle plates 36.

The illustrated embodiment of the invention may be modified in construction and arrangement without departing from the scope of the invention as defined in the 45 appended claims.

I claim:

1. A glass annealing lehr comprising a tunnel having a bottom, a flexible endless conveyor having its ware-bearing strand extending through said tunnel and in contact with said bottom, a sprocket chain secured to each edge of said conveyor, and mechanism for driving said chains.

2. A glass annealing lehr comprising a tunnel having a bottom, a flexible endless conveyor of woven wire fabric having its ware-bearing strand extending through said tunnel and in contact with said bottom, a sprocket chain secured to each edge of said conveyor, and a driving mechanism for said conveyor including sprocket wheels for engagement with said chains.

3. A glass annealing lehr comprising a tunnel having a metallic bottom, a flexible endless conveyor having its ware-bearing

strand extending through said tunnel and in contact with said bottom, a sprocket chain secured to each edge of said conveyor, and a driving mechanism for said conveyor including sprocket wheels for engagement 70 with said chains.

4. A glass annealing lehr comprising a tunnel, a conveyor for transporting glassware through said tunnel and having the side edges thereof extending laterally without said tunnel, a sprocket chain secured to each edge of said conveyor, and mechanism 75 for driving said chains.

5. A glass annealing lehr comprising a tunnel having a bottom, a conveyor for 80 transporting glassware through said tunnel, said conveyor having its ware-bearing portion supported directly by the bottom of the tunnel and having its edge portions extending without the tunnel, a sprocket chain secured to each edge of said conveyor, and a driving mechanism for said conveyor including 85 sprocket wheels engaging said chains.

6. A glass annealing lehr comprising a 90 tunnel having the said walls spaced from the bottom thereof, a conveyor for transporting glassware through said tunnel and having its side edges extending beneath said tunnel walls, a sprocket chain secured to each edge of said conveyor, and a driving mechanism for said conveyor including 95 sprocket wheels engaging said chains.

7. A glass annealing lehr comprising a 100 tunnel, a conveyor for transporting glassware through said tunnel and having the side edges thereof extending laterally without the tunnel, sprocket chains carried by the side edges of said conveyor, a track mounted exteriorly of said tunnel adapted 105 to support said chains, and a driving mechanism for said conveyor including sprocket wheels engaging said chains.

8. A glass annealing lehr comprising a 110 tunnel having a bottom, side walls and top, a support extending longitudinally along each side of said tunnel and exteriorly thereof and adapted to support said side walls in spaced relation to said bottom, a conveyor for transporting glassware through said tunnel and having the edge portions extending laterally beneath said side walls, a sprocket chain secured to said side edges of said conveyor and carried 115 by said support, and a driving mechanism 120 for said conveyor including sprocket wheels for engagement with said chains.

9. A glass annealing lehr comprising a 125 tunnel having a bottom, side walls and top, a conveyor for transporting glassware through said tunnel consisting of a plurality of pans mounted to slide on the bottom of said tunnel and having their side edges 130 extending without the tunnel between the bottom and walls thereof, chains connecting

the outer edges of said pans, and means for driving said chains to advance 15
said chains to advance the conveyor through said tunnel.

10. A glass annealing lehr comprising a
5 tunnel having a bottom, side walls and top,
a conveyor for transporting glassware
through said tunnel consisting of a plurality
of pans of open work structure, having
10 their ware-bearing portions supported
throughout their length and breadth by the
bottom of said tunnel and having their side
edges extending without the tunnel between
the bottom and walls thereof, chains connect-
ing the outer edges of said pans, and

means for driving said chains to advance 15
the conveyor through said tunnel.

11. A glass annealing lehr comprising a
tunnel having a metallic bottom, side walls
spaced above and laterally beyond said bot-
tom, Z bars for supporting said walls, a con-
veyor for transporting ware through said
tunnel and consisting of a plurality of pans
having their edges projecting beneath said
side walls, and chains connecting said pans
and riding on said Z bars. 20

Signed at Hartford, Connecticut, this
25th day of August, 1925.

VERGIL MULHOLLAND.
